UNITED STATES PATENT OFFICE.

JAMES HUDSON, OF BIRMINGHAM, ENGLAND.

DRAW-PLATE.

SPECIFICATION forming part of Letters Patent No. 569,335, dated October 13, 1896.

Application filed May 11, 1896. Serial No. 591,100. (No model.)

To all whom it may concern:

Be it known that I, JAMES HUDSON, a citizen of Great Britain, and a resident of 187 Monument Road, in the city of Birmingham, 5 England, have invented a certain new and useful Improvement in the Manufacture of Tubes, of which the following is a specification.

This invention relates to an improvement 10 in the manufacture of tubes, my object being to provide simple and effective means for removing the tube from the drawing-down bar, after the metal has been reduced to the required gage or thickness, without bruising 15 or damaging either the bar or the tube.

In order that my invention may be the more 20 readily understood, I append one sheet of explanatory drawings, to be hereinafter referred to.

25 Figure 1 is a front elevation, Fig. 2 an end elevation, and Fig. 3 a plan, illustrating my tube-withdrawing appliance. Figs. 4 and 5 are sectional views, to a larger scale, of the tube and bar, illustrating the process of withdrawal.

The same reference-letters in the different 30 views indicate the same parts.

I place the tube requiring to be drawn down upon a bar of any ordinary form and draw 35 both tube and bar together through the die upon a tube-bench or like machine arranged in the usual manner. After the tube and bar have been thus drawn together through the die I remove the ordinary die and die-block 40 from its working position and replace it with the withdrawing-block A, having a die mounted therein.

The withdrawing-die is formed in two parts 45 B B', and I provide screws C C' for the purpose of adjustment. The adjacent edges of the parts B B' of the die do not touch or meet, being kept apart by the distance-pieces D D', but a space d d' is left at each side of the die, as illustrated at Fig. 1. Lateral or 50 side movement of the die parts B B' and the distance-pieces D D' is prevented by the ribs E E'.

The front edges of the die parts B B' are well rounded to admit the tube, and the longi-

tudinal edges are treated in like manner to 50 prevent any cutting or damage to the exterior surface of the tube. The diameter of the die, when the two parts B B' are set in their working position, is somewhat less than the external diameter of the tube which has 55 been passed through the drawing-down die.

On drawing the tube F and bar G through the withdrawing-die the top and bottom portions of the tube-metal in contact with the die are subjected to compression, and 60 such compression forces the sides of the tube into the spaces d d' between the die parts, thus forming the projections or excrescences f f', as at Fig. 4. After the tube has been thus once drawn completely through the ex- 65 tractor-die I slightly increase the diameter of the die by adjustment of the screws C C', and I then again draw the tube and bar through the die, but with the projections or excrescences f f' in contact with the die parts. 70 Such second drawing of the tube and bar through the withdrawing-die returns the tube to its circular section, as shown at Fig. 5, and at the same time sufficiently loosens the tube as to permit of its ready withdrawal 75 from the bar G.

Having thus described my invention, I declare that what I claim, and desire to secure by Letters Patent, is—

1. In combination, in means for removing 80 tubes from mandrels, a pair of non-rotary dies having curved bearing-surfaces and arranged with laterally-extending openings between them, and distance-pieces in said openings between the dies, substantially as described.

2. The combination of a block A fitted with adjustment-screws C C', of the two die parts B B' having distance-pieces D D' interposed between them and with spaces d d' on each 90 side, substantially as set forth.

In witness whereof I have hereunto set my hand in presence of two witnesses.

JAMES HUDSON.
